UNITED STATES PATENT OFFICE.

HENRY J. HERBERT, OF DETROIT, MICHIGAN.

DESIGN FOR A BACK FOR MIRRORS, BRUSHES, OR SIMILAR ARTICLES.

No. 39,455.

Specification for Design.

Patented Aug. 25, 1908.

Application filed May 1, 1908. Serial No. 430,417. Term of patent 7 years.

To all whom it may concern:

Be it known that I, HENRY J. HERBERT, a citizen of the United States of America, residing at Detroit, in the county of Wayne and State of Michigan, have invented a certain new, original, and ornamental Design for a Back for Mirrors, Brushes, or Similar Articles, of which the following is a specification, reference being had therein to the accompanying drawings, forming part thereof.

The figure is a plan view of a mirror back, showing my new design.

The salient features of the design reside in the particular contour of the back and handle, and the surfacing of the parts to represent alligator skin.

I claim:

The ornamental design for a back for mirrors, brushes or similar articles, as shown.

HENRY J. HERBERT.
